UNITED STATES PATENT OFFICE.

ROBERT McGREGOR, OF ILFORD, ENGLAND, ASSIGNOR OF ONE-THIRD TO CLAYTON AND SHUTTLEWORTH LIMITED, OF LINCOLN, ENGLAND, AND ONE-THIRD TO PHILIP WARWICK ROBSON, OF LINCOLN, ENGLAND.

BAFFLE FOR HEAT-EXCHANGE APPARATUS.

Application filed March 14, 1922. Serial No. 543,752.

To all whom it may concern:

Be it known that I, ROBERT McGREGOR, a subject of the King of Great Britain and Ireland, and residing at 158 Balfour Road,

5 Ilford, in the county of Essex, England, have invented certain new and useful Improvements in Baffles for Heat-Exchange Apparatus, of which the following is a specification.

10 The present invention relates to water tube boilers and similar apparatus in which it is desired to effect an exchange of heat between a fluid contained in tubes and a second fluid outside the tubes. In such apparatus if the tubes are arranged in rows with passages between the full exchange of heat is not realized owing to the fact that there is a tendency for the fluid circulating around the tubes to pass along the passages

15 formed between the rows without giving up or taking in heat to or from the tubes as the case may be in the manner desired.

Hitherto it has been proposed to overcome this difficulty by inserting between the tubes 25 baffle plates of a curved or angular section partly surrounding the said tubes or by the use of a series of baffle plates of rectangular section inclined to the tubes which when in position form a solid wall for reflecting the 30 fluid surrounding the tubes. These arrangements are objectionable by reason of the difficulty of making replacements, and the object of the present invention is to overcome this difficulty and enable apparatus of 35 the type mentioned to be operated with an efficiency as high as is the case in which tubes placed in staggered relationship are employed.

The invention consists in a heat-exchange 40 apparatus in which are provided tubes arranged in vertical rows with passages therebetween and deflectors situated in said passages, said deflectors being inclined to said tubes alternately in opposite directions.

45 Various forms of the invention are illustrated by way of example in the accompanying drawings, in which:—

Figure 1 is a longitudinal view of the tubes of a water tube boiler showing the 50 deflectors in position;

Figure 2 is a section on the line A—B of Figure 1;

Figure 3 is a section as regards its left-hand half on the line C—D and as regards its right-hand half on the line E—F of 55 Figure 1;

Figures 4 to 7 are views similar to Figure 1 illustrating modifications of the invention;

Figures 8 and 9 are views similar to Figures 1 and 2 showing a further modification. 60

In the form of the invention depicted in Figures 1 to 3, deflector plates 1 are placed between the tubes 2 so that alternate plates are inclined in opposite directions as indicated. The effect of this is to cause the flue 65 gases which would otherwise pass substantially straight up the passages between the rows of tubes 2 to be diverted through the horizontal spaces existing between the tubes in the manner indicated by the arrows. 70

A convenient form of deflector 1 is shown in Figures 1 and 2 and consists of a plate the width of which along the greater part of its length is substantially the same as that of the passages between the tubes. Near 75 the ends, however, the plate is formed with lateral extensions 3 shaped so as to rest on the top and bottom tubes in the manner illustrated. These deflector plates are readily inserted edgewise between the rows of 80 tubes and may then be turned into the position indicated so as to produce the required baffling effect on the flue gases. If the tubes 2 be of relatively great length we may, as indicated in Figure 4, employ two or any 85 larger number of sets of deflector plates.

It will be noticed from Figures 1 to 4 that in order to prevent too excessive baffling of the gases we prefer to make the deflectors of such a length that their lower ends do not 90 extend as far as the ends of the tubes. This, however, is not an essential feature, since we may find it in certain cases desirable to make the deflectors extend at both ends to the ends of the tubes 2 or, as indicated in Figure 5, 95 we may prefer to leave spaces both at the upper and lower ends of the deflector plates. It is not necessary that the deflector plates should be straight and in Figures 6 and 7 we have illustrated two other suitable forms. 100

In Figure 6 each deflector plate extends from one end of the tubes horizontally to approximately their mid length and then descends vertically through the length of the

whole stack, finally becoming horizontal so as to extend under the other half of the stack of tubes.

In Figure 7 we have shown deflector plates which are of curved contour.

In either of these constructions the action is essentially the same as that described with the use of flat plates, namely to cause the flue gases to be laterally deflected through 10 horizontal spaces between the tubes.

Figures 8 and 9 illustrate a modified form of flat plate in which the lower edges of the lateral extensions 3 are formed at such an angle as to give a wedging action between 15 the tubes upon which they rest, thus helping to maintain the plates in position. These figures also illustrate the employment in the case in which the plates 1 do not extend across the whole length of the tubes 2 of 20 covers 4 which may be placed over the spaces between the upper ends of the plates 1 and the ends of the tubes 2 in order to prevent lodgment of soot or the like.

While the invention has been described in 25 connection with heat-exchange apparatus in general it will be evident that it is applicable

to all kinds of apparatus such for example as boilers, superheaters, fuel economizers, cooling apparatus or the like.

Claims:

1. In a heat-exchange apparatus, tubes arranged in vertical rows with passages therebetween and deflectors situated in said passages, said deflectors being inclined to said tubes alternately in opposite directions. 30

2. In a heat-exchange apparatus, tubes arranged in vertical rows with passages therebetween and deflectors situated in said passages, said deflectors being inclined to said tubes alternately in opposite directions and 40 of substantially the same width as said passages.

3. In a heat-exchange apparatus, tubes arranged in vertical rows with passages therebetween, and deflectors formed of plates 45 having their length considerably greater than their width situated in said passages, said deflectors being inclined to said tubes alternately in opposite directions.

In testimony whereof I have signed my 50 name to this specification.

ROBERT McGREGOR.
